UNITED STATES PATENT OFFICE.

MILLARD WINFIELD GRIGG, OF FORT MILL, SOUTH CAROLINA.

DESIGN FOR A DENTAL-ENGINE HANDPIECE ATTACHMENT.

SPECIFICATION forming part of Design No. 35,080, dated September 10, 1901.

Application filed April 20, 1901. Serial No. 56,771. Term of patent 7 years.

To all whom it may concern:

Be it known that I, MILLARD WINFIELD GRIGG, a citizen of the United States, residing at Fort Mill, in the county of York and State of South Carolina, have invented and produced a new and useful Design for a Dental-Engine Handpiece Attachment, of which the following is a specification.

The leading feature of my design resides in the peculiar shape and formation of the various parts hereinafter fully described, and pointed out in the claim.

In the drawings forming part of this specification, Figure 1 is a perspective view. Fig. 2 is a top plan view. Fig. 3 is a bottom plan view. Fig. 4 is a side view.

Referring especially to the drawings, A indicates the shank, having the head B arranged at a right angle to the shank A. A divided sleeve or collar C is formed upon the

rear end. The shank A is given a compound curve, being elevated, as shown at A', and depressed, as shown at A''. The head B is curved throughout its entire length, as shown at B'. The forward edges of the collar C are curved, as shown at C', and the meeting edges of the said collar are beveled, as shown at C''. Where the collar C joins the shank, a curve C''' is produced, and a curve A''' is produced at the juncture of the shank and head.

Having thus fully described my invention, what I claim as new, and desire to secure by Letters Patent, is—

The design for a dental-engine handpiece attachment, substantially as herein shown and described.

MILLARD WINFIELD GRIGG.
